UNITED STATES PATENT OFFICE.

GEORGE FREDERICK DARLING, OF BRIARBRAE, CAWNPORE, BRITISH INDIA.

AXLE-BOX COVER FOR RAILWAY OR LIKE VEHICLES.

Application filed October 6, 1925, Serial No. 60,838, and in India March 7, 1925.

This invention relates to an automatically locking cover to an axle-box for a railway or like vehicle, which cover is of the kind which when once closed cannot be opened again without lifting the wagon or at least lifting the vehicle spring which rests upon the axle-box concerned.

Axle-boxes are known in which the cover slides into place and can only be closed by lifting the vehicle spring, slipping the cover into position with the upper end of the cover, or an extension thereof, extending under a part of the vehicle spring and lowering the said spring into position again. In this known apparatus the cover cannot either be placed in position or opened without having to lift the vehicle spring.

Now this known method of fastening has been found inconvenient and it is an object of this invention to provide an arrangement which can be closed at any time by simply slipping or moving the cover into place, which cover has on the inside a hinged flap, spring catch or the like, which, when the cover is in closed position, automatically engages the axle-box so as to prevent removal of the cover. To remove the cover the hinged flap or catch is operated to release the cover by means of levers, bell-cranks or the like inside the axle-box which can be worked from the outside of the axle-box by pulling on the stem, or causing the stem of the releasing arrangements to protrude through a hole in the upper surface of the axle-box, which stem end is covered by and prevented from being operated, or operating, owing to the vehicle spring holding it down. In order therefore to release the cover the vehicle spring must first be raised. Usually a spring will be fitted to cause the stem of the releasing arrangement to automatically protrude when the vehicle spring is released.

One object of the invention is by the above described means to provide an axle-box which is fool-proof and practically thief-proof. Railway axle-box thieves are not provided with the necessary appliances for lifting the wagon sufficiently to release the axle-box cover. The arrangement will thus defeat their activities and save the railways concerned enormous expense in theft and damage to rolling stock.

The invention not only includes the axle-box cover but also axle-boxes so fitted and adapter means whereby any ordinary axle-box may be altered to make it capable of

being fitted with a cover of the kind indicated.

The invention thus consists of an improved automatically locking cover for an axle-box of a railway or like vehicle which may be slid or moved into its closed position and is automatically locked therein by a hinged flap, catch or device which, actuated by gravity or under the action of a spring, drops, moves or springs forward so that it engages the axle-box or the side or edge of the opening in the axle-box to prevent the cover being opened until or unless a releasing device is operated, characterized by the said releasing device being so arranged that it can only operate, or be operated, to release the said cover when the vehicle spring, normally resting upon the top of said axle-box, is lifted clear of the same.

The invention also comprises the necessary disengaging device fitted inside the axle-box and normally arranged to be in an inoperative position as long as the vehicle spring engages the top of the box, and which has a stem or part passing through or lying in a hole in the top of the box which is held depressed by said spring, but which, upon the said spring being raised or lifted clear of the box, is capable of being lifted, or of being forced up by a spring, to operate the said hinged flap, catch or device to move the same into its disengaging position to release the cover.

In the preferred form the cover slides into a grooved recess and is secured therein, when in closed position, by a locking device inside the cover falling or being pushed out to engage the inner upper side of the opening.

The cover may slide into a grooved recess made integral with the axle-box itself if a new axle-box is being made. It may, on the other hand, slide into a grooved recess which is formed by, or made in, an adapter frame fitted to the front of the axle-box, whereby an axle-box of any known pattern may be adapted to automatically lock in the manner substantially as indicated. Such adapter frame according to this invention will preferably be welded onto the face of the axle-box and become one therewith.

The disengaging device may have spring means adapted to cause the stem to protrude above the upper surface of the axle-box upon the vehicle spring being lifted to allow of such movement and said device at the same

time causing the cover locking means to be released.

The invention will now be described with reference to the accompanying drawings which show, by way of example only, various forms the invention may take. In these drawings:—

Figure 1 is a cross section of an axle-box with the cover in place but the vehicle spring removed.

Figure 2 is a plan.

Figure 3 is a side view of another form the disengaging device may take, and

Figure 4 is an end view partly in section. In the embodiment shown in Figures 1 and 2 the axle-box 1 has a sliding cover 2 which slides into grooved recesses 3. The recesses are (in Fig. 1) formed in an adapter 4 secured to the axle-box but may with advantage in new axle-boxes be made integral with the main casting.

The cover slides into place from above and according to the usual arrangement of axle-boxes on Indian railways has a slight inclination backwards. A flap or catch 5 is hinged at 6 to the inside of the cover 2.

Whilst the cover is being pushed into position the flap 5 lies in a depression or recess 7 in the cover. This recess may be made by the thickened reinforced edge 8 of the cover. Upon the cover reaching its final closed position the flap or catch 5 falls by gravity and takes up a position 5^a.

In its new position 5^a the flap or catch 35 prevents the cover being raised or opened again as its top engages the inside of the axle-box.

The upper edge of the cover may be turned over as shown at 9 to prevent a tool or feeler being forced in to operate the flap 5.

It will thus be seen that the cover automatically locks itself in position and cannot be unlocked from the front.

To release the cover an operating rod 10 is provided having a stem or button 11 projecting through a hole in the top of the axle-box casing.

This operating rod 10, on being pulled or raised, operates a bell-crank 12 pivoted at 13, which bell-crank in turn operates the push rod 14. The push rod 14 has a slot or other supporting surface in it which is supported by the stud 15 and has a cranked end 16 which, on being pushed when the rod 10 is pulled, operates to press back the flap 5, thus releasing the cover.

A spring 17 may be provided to cause the rod 10 to rise when it is permitted so to do.

The stem or button 11 is however arranged to come below the vehicle spring, which spring is normally seated in the recess 18. The rod 10 can thus only be operated, or operate, to release the cover when the vehicle spring has been raised off its seating 18.

In Figures 3 and 4 the releasing device is

slightly different. The bell-crank 12 is reversed so that the rod 14 is in tension when about to release the flap. This rod 14 operates a rocker arm 19 on the rocker bar 20, which rocker bar is much stiffer than the end 16 owing to its being pivoted at 21, 22 in bearings fixed to the two sides 23, 24 of the axle-box. The release arm 25 in this case causes the flap 5 to release.

It will of course be understood that the invention is not limited to the embodiments illustrated which are only shown by way of example, but will include within its scope reasonable modifications. For example, any suitable kind of sliding, pivoted or hinged cover could be used. A small spring might be fitted between the flap 5 to cause it positively to open. The rocker arm 20 may be arranged at the level of the upper edge of the opening in the axle-box so as not to obstruct the operation of packing the cotton waste into the box.

Other alterations might be made. For example, in order to avoid any possibility of a hinged flap, if used, getting gummed up with oil, or owing to the suction produced due to a film of oil between the said flap and the back of the axle-box cover, a button, serrations or the like might be formed to prevent the flap from coming into close contact with the cover, or a small spring might be introduced certainly to overcome the suction of a film of oil between the said parts.

A guard or projecting rim may be cast upon, or otherwise fixed to, the upper surface of the axle-box to guard or surround the orifice through which the button or rod stem 11 passes, which, without necessarily touching the underside of the spring, will allow so little clearance that it will prevent the said button or stem being tampered with.

Having now particularly described and ascertained the nature of my said invention and in what manner the same is to be performed, I declare that what I claim is:—

1. In a railway axle box, a removable cover therefor, a latch for automatically securing the cover in closed position, and latch operating means housed within the axle box, which means is only operable to release the cover latch when the load normally superimposed upon the axle box is removed.

2. In a railway axle box, a removable cover therefor, a latch for securing the cover in its closed position, the latch being fastened to the cover and having a bias to automatically assume its latching position when the cover is closed, and a latch operating means housed within the axle box and operable to automatically release the cover latch only when the vehicle spring normally resting upon the top of the axle box is lifted clear of the same.

3. In a railway axle box provided with a

cover element or lid to give access to the interior of the box for inspection, renewal, or repair of the bearing, a latch to secure the cover in its closed position, the latch being arranged entirely within the axle box, and latch releasing means comprising a system of connected rods and levers which are also housed and supported within the axle box, one of the rods of the system being vertically supported and alined with an opening in the top of the axle box, a spring element associated with the said rod in a manner to raise the rod and thereby release the cover latch when the vehicle load which normally rests upon the top of the axle box is lifted.

4. In a railway axle box provided with a sliding cover to close the box against unauthorized tampering, a pivoted latch carried by the cover and arranged to lie with-

in a recess in the under side of the cover in order not to interfere with the sliding movement of the cover to its closed position, the latch moving automatically to a holding position when the cover is closed, and latch releasing means comprising a system of connected rods and levers which are also housed and supported within the axle box, one end of the system being arranged to engage and move the latch into its release position, and the other end of the system consisting of a rod vertically supported and alined with an opening in the top of the axle box, and a spring element tending to raise the rod and thereby operate the latch releasing means when the vehicle load which normally rests upon the top of the axle box is lifted.

In testimony whereof I hereto affix my signature, this twentieth day of August, 1925.

GEORGE FREDERICK DARLING.
